UNITED STATES PATENT OFFICE.

WILLIAM E. CLARK, OF CHARLESTOWN, NEW HAMPSHIRE, ASSIGNOR TO
CONTINUOUS RAIL JOINT COMPANY OF AMERICA, A CORPORATION
OF NEW JERSEY.

INSULATED RAIL CONNECTION.

SPECIFICATION forming part of Letters Patent No. 737,350, dated August 25, 1903.

Application filed May 8, 1902. Serial No. 106,437. (No model.)

To all whom it may concern:

Be it known that I, WILLIAM E. CLARK, a citizen of the United States, residing at Charlestown, in the county of Sullivan and 5 State of New Hampshire, have invented certain new and useful Improvements in Insulated Rail Connections; and I do hereby declare the following to be a full, clear, and exact description of the invention, such as 10 will enable others skilled in the art to which it appertains to make and use the same, reference being had to the accompanying drawing, and to letters of reference marked thereon, which form a part of this specification.

15 The objects of this invention are to provide a compact, durable, and efficient insulated connection for railway-rails to enable the metal connecting-plates to be easily rolled without undue expense, particularly in the 20 construction and maintenance of the rolls, and to secure other advantages and results, some of which may be referred to hereinafter in connection with the description of the working parts.

25 The invention consists in the improved insulated rail connection and in the arrangements and combinations of parts, all substantially as will be referred to hereinafter in connection with the description of the working 30 parts.

Referring to the accompanying drawing, the single figure of which represents a rail and connections by which one section thereof is joined to the next in longitudinal alinement therewith, *a* indicates the head of the rail, having at the top a suitable tread-surface for the car-wheels. *b* represents the web of the rail, which is perforated to permit the passage therethrough of the bolts, and *c* indicates the 35 flange extending horizontally in opposite directions from the bottom of said web.

40 *d d* indicate two blocks, bars, or billets of electrically insulating matter, preferably wood, which fit closely between the head and flange of the rail and extend laterally out from the recesses between said parts to a point approximately in vertical line with the outer edges of the flange *c*. Said blocks, bars, or billets *d* are horizontally perforated in line or 45 correspondence with the bolt-holes of the web.

and at their upper and lower surfaces are provided with inclined surfaces *e* and *f* to engage the head and flange of the rail, the said blocks bars, or billets being thus of a wedge shape and adapted to be forced tightly into the recess 55 between said parts when the bolts *g* are screwed up. At the outer sides of the said bars, billets, or blocks *d* the same are oppositely beveled, as at *h i*, to receive correspondingly-inclined bearings of the plates *j j*, hereinafter 60 referred to. Said plates *j j* each comprises a vertical perforated flange *k* and outwardly and downwardly inclined or curved web or connection *l* and an inward horizontal flange. The vertical flange is preferably provided at 65 its inner side, at or near the top and bottom thereof, with longitudinal ribs *n o*, with inclined bearings *p q* disposed oppositely to form a recess with inclined upper and lower walls, into which the wedge-like outer sides of the 70 block, billet, or bar *d* may enter and be rigidly wedged and held. The outwardly curved or inclined web or connection *l* forms with the flange *m* in each plate *j* a longitudinal groove *r*, so disposed as to lie in the horizontal plane 75 of the flange *c*, said groove being somewhat wider vertically than the flange *c* at its edge, so that a chamber may be formed around the said flange edge, as indicated in the drawing. The curved or inclined web or connection *l* 80 forms a downwardly and outwardly inclined walls at the top of the groove *r*, and thus the groove is flaring. Between the bottom of the rail or the flange *c* thereof and the flanges *m* is interposed a piece of sheet insulation *t*. 85 This is somewhat wider than the flange *c*, and the opposite edges are bent or turned up and around the edges of said flange, and when the bolts *g* are screwed up the returned parts *u*, engaging the walls *s*, are forced downwardly 90 hard against the top of said flange. Thus the rail-flange is electrically insulated from the connecting-plates *j j*; but said flange is firmly supported by said plates and the edges firmly gripped thereby, all of which conduces 95 to great firmness and rigidity of connection, and a smooth running of the car is coupled with proper electrical insulation. A sleeve of insulation *v* is preferably employed around the bolt *g* within the bolt-hole of the web. 100

The bolt *g* when arranged through the holes of the parts *b d d j j* and the nut *w* thereof is screwed up, draws the several parts firmly together, and any wear on said parts may be taken up by further screwing.

5 I am fully aware that detail variations from my above-described construction may be made without departing from the spirit or scope of the invention, and I do not wish to be understood as limiting myself by all the positive descriptive expression employed herein, excepting as the state of the art may require.

Having thus described the invention, what I claim as new is—

15 The combination with the meeting ends of two rails, of fish-plates applied longitudinally on the opposite sides of said rails, each comprising a flat horizontal base member extending beneath the rail-base, a narrow doubled 20 or V-shaped portion inclosing the outer edge of the rail-base flange, and a vertical portion extending upward from the top of said doubled portion parallel to the web of the rail

and being longitudinally recessed at its side next the rail, a sheet of insulating material 25 arranged between the bottom of the rail and the base members of the fish-plate and having its edges bent over the edges of the base-flanges of the rail within the doubled portions of the fish-plate, insulating blocks or billets 30 between the webs of the rails and the vertical portions of the fish-plate, said blocks having longitudinal tapered ribs at their outer sides entering the recesses of the vertical portions of the fish-plates, and clamping-bolts 35 extending transversely through said blocks or billets, vertical portions of the fish-plates and webs of the rails.

In testimony that I claim the foregoing I have hereunto set my hand this 19th day of 40 April, 1902.

WILLIAM E. CLARK.
